UNITED STATES PATENT OFFICE.

JAMES BLAINE FISHER, OF WAUKESHA, WISCONSIN, ASSIGNEE TO WAUKESHA MOTOR COMPANY, OF WAUKESHA, WISCONSIN, A CORPORATION OF WISCONSIN.

BREATHER-TUBE AND CAP THEREFOR.

1,298,922.

Specification of Letters Patent. Patented Apr. 1, 1919.

Application filed May 16, 1917. Serial No. 168,997.

To all whom it may concern:

Be it known that I, JAMES BLAINE FISHER, a citizen of the United States, residing at Waukesha, in the county of Waukesha and 5 State of Wisconsin, have invented a certain new and useful Improvement in Breather-Tubes and Caps Therefore, of which the following is a full, clear, concise, and exact 10 description, reference being had to the accompanying drawings, forming a part of this specification.

The present invention relates broadly to internal combustion engines, and has particular reference to new and useful improvements 15 in breather caps for use in connection therewith.

The device known as a breather is installed on the crank case of the engine and its function is to permit the introduction of 20 the required amount of lubricating oil to the case and to permit the escape of gases from the crank case without the escape of oil. A detachable cap is usually provided for the breather. However, this cap very often 25 becomes lost or when hinged to the breather is left open and consequently an amount of sand and other foreign matter enters the crank case impairing the efficiency of the lubricant, necessitating frequent cleaning.

30 An object of my invention is to provide a new and improved cap and retainer for association with the breather to reduce the cost of manufacture of the same and increase its efficiency. When hinged caps are employed 35 the projection of the hinged parts very often are located in the way of other parts of the engine, and therefore another object of my invention is to provide a breather cap and fastening which may be adjusted to different 40 positions so as not to interfere with the other parts of the engine.

While the improvement of my invention has particular reference to a breather cap, my invention also extends to the entire structure of the breather which is compact, strong 45 and durable, cheap to manufacture and capable of installation in any position in which the present breather may be installed.

Other objects and advantages of my invention not hereinbefore set forth will appear from the following detailed description of the same, taken with an inspection of the accompanying drawings.

Figure 1 is a fragmental elevational view

of one side of an internal combustion engine 55 showing the usual position of the breather embodying the improvement of my invention;

Fig. 2 is a vertical section of the breather showing the cap in closed position; and 60

Referring more particularly to the drawings, wherein similar characters of reference designate like and corresponding parts throughout the various views and referring specifically to Fig. 1, I have illustrated a 65 portion of an internal combustion engine structure showing the cylinders, a portion of the crankcase, designated respectively, C and C'. The breather is mounted adjacent the cylinder on the crank case and is designated B in its entirety, the breather shown being that of my invention.

The breather of my invention preferably embodies a tubular body 10 having the lower end thereof externally threaded as at 11 for 75 reception in an opening provided in the crank case, a flange 12 being formed adjacent the threaded portion to limit the inward movement of the body. A plurality of 80 downwardly directed baffle plates 13, 14 and 15 are provided on the interior peripheral base of the tubular body. The body has been shown as cylindrical, but, of course, this is not strictly essential. The upper end of the body is flared as at 16 to provide a mouth, 85 the mouth being strengthened by an enlarged ridge or flange 17. The portion of the mouth below the flange 17 is polygonal in shape as at 18 so as to receive a wrench or the like for screwing the body into position.

The cap or closure is supported by detachable means comprising the lug 19 formed integrally with the body 10 and projecting radially interiorly thereof, said lug being provided with a threaded opening 20 in alignment with the longitudinal axis of the body. A sleeve 21 is provided, one end of the sleeve being threaded as at 22 for reception in the opening 20, the free end of the sleeve projects a trifle beyond the top of the cap 28 to prevent the cap from rattling when closed.

The sleeve 21 is intended to receive the cap carrying rod 24, said rod having one free end thereof provided with a notch 25 105 and the opposite free end thereof provided with an eye 26, the rod being curved laterally as at 27 for a purpose which will

hereinafter appear. The notched end of the rod is adapted for reception in the sleeve and is therefore slightly bowed so that when the same is forced into the sleeve the bolt portion will cause the notch on the end of the rod to engage under the end of the sleeve. The curved portion 27 of the rod will limit the downward movement of the rod in the sleeve, but will permit rotative movement of said rod in said sleeve.

5 The closure or cap 28 is concavo-convex in cross section and is provided with a concentric sleeve portion 29 provided with a bore 30. A seating flange 31 is formed preferably on the margin of said cap. The sleeve 21 is receivable in the bore 30 of the cap and the cap is adapted to be moved upon said rod to open and close the mouth of the breather.

10 In use the breather is installed as shown in Fig. 1. To fill the crankcase with a lubricant the cap is moved into the dotted line position shown in Fig. 2. Should the user neglect to close the cap the first few revolutions of the engine will, owing to the vibration, cause the cap to fall into the closed position.

15 Of course, the breather is not limited to the use set forth, but is capable of application to various driving and driven devices having oil chambers or the like in which gases are apt to gather. However, the device is primarily designed to take care of the gases in the crank case of an internal combustion engine which would otherwise escape elsewhere carrying the lubricant with it. When the engine is running and any gas collects in the crankcase, such gas may readily escape by forcing open the cap, said cap at the same time preventing the entrance of dust, sand or other foreign matter to the crank case. The device may be assembled quickly and the rod 24 is adjustable through a horizontal plane so as to escape adjacent parts of the engine.

20 I do not limit my invention to the exact details of structure disclosed but reserve the right to make such changes therein as do not depart from the spirit and scope of the invention as claimed.

I claim:

1. In combination, a breather tube having a plurality of baffles on the inner surface thereof, a lug projecting interiorly radially of the tube and having a threaded opening therein concentric with the longitudinal axis of the tube, a threaded sleeve receivable in said opening and projecting from the upper end of said tube, a curved rod having a notched end receivable in said sleeve, and a cap receivable on said rod.

2. In combination, a tubular body provided with a plurality of baffles interiorly thereof, a lug in said body having a threaded opening, a sleeve receivable in said open-

ing, a curved rod for reception in said sleeve, an apertured cap receivable on the rod and adapted to close the mouth of said body and means to limit the movement of said cap on said rod.

3. In combination, a tubular body provided with a plurality of baffles on the inner face thereof, a lug in said body having a threaded opening, a sleeve receivable in said opening, a curved rod for reception in said sleeve, a cap having an aperture through which said rod is adapted to pass, said cap being slidable vertically and laterally on the rod, means to limit the movement outwardly of said cap on said rod, and means to retain said rod in said sleeve.

4. In combination, a tubular body having a flaring mouth and a lug formed interiorly of the body, said lug having a threaded opening concentric with the longitudinal axis of the body, a sleeve anchored in said opening and extending toward the mouth, a rod having vertical and lateral portions, the former portions being receivable in said sleeve, and having a notch to engage under the end of the sleeve, a closure cap receivable on the sleeve and rod and the free end of said rod being formed to retain said cap against displacement.

5. In combination, a tubular body having a threaded end and a flaring mouth and a lug formed interiorly thereof, said lug having a threaded opening concentric with the longitudinal axis of the body, said body being receivable on a crank case or the like, a sleeve anchored in said opening and extending toward the mouth, a rod having lateral and vertical portions, the lateral portion receivable in said sleeve, means on the rod to engage the sleeve the vertical portion of said rod being bowed so as to cause said means to engage said sleeve, a cap receivable on the rod and adapted to be disposed on the lateral portion thereof when in opened position and means on the free end of the rod to prevent displacement of the cap.

6. In combination, a breather having a plurality of baffle plates mounted on the inner periphery and a radially extending lug mounted at the upper end, said lug having an aperture therein, a rod adapted to be mounted in said aperture, a cap slidably mounted on said rod and adapted to adjust its position in relation to the internal condition of said breather.

7. In a breather of the kind described, a tubular body, a lug formed on the inner face of the body, fixed supporting means extending axially from said lug, and an apertured closure for said body slidable on said supporting means, and normally seating on the mouth of said tubular body.

8. In a breather of the kind described, a tubular body, a lug on the inner face of the body, fixed closure-retaining means extend-

ing axially from said lug, a closure freely movable on said retaining means and normally seating on said tubular body.

9. In a breather of the kind described, a tubular body having a mouth, a lug formed on the inner face of the body, fixed supporting means extending axially from said lug, a closure for said mouth freely movable vertically on said supporting means 10 and adapted to be held on its seat by gravity.

10. In a breather of the kind described, a tubular body having a mouth, a lug formed on the inner face of the body, a closure for said mouth, means carried by said lug for 15 guiding the closure to one side as it is raised, said guide means being circumferentially adjustable.

11. In a breather having a breather opening, a closure therefor adapted normally to 20 rest in closed position, means for retaining said closure centrally relatively to said opening, guide means extending through the closure for positioning it at one side of the opening when lifted, said closure being

freely returnable to closed position by 25 gravity.

12. In a breather having a breather opening, a closure for said opening, means preventing lateral displacement of the closure when in closing position, guide means projecting through the closure and adapted to 30 position the closure at one side of the breather when lifted, said closure being freely returnable from its open position to its closing position by gravity. 35

13. In a breather having a breather opening, a closure for said opening, fixed means preventing lateral displacement of the closure when in closing position, a curved guide rod extending through the closure for 40 positioning the closure at one side of the breather when raised to open position, said closure being adapted to be easily dislodged from its open position by a slight jar.

In witness whereof, I hereunto subscribe 45 my name this 9th day of April, A. D. 1917.

JAMES BLAINE FISHER.
